(57) **CLAIM**

The ornamental design for a sports bra, as shown and described.

DESCRIPTION

FIG. 1 is a front and right perspective view of a sports bra; FIG. 2 is a front view thereof with the straps of the sports bra crossed;

FIG. 3 is a rear view thereof;

FIG. 4 is a right view thereof;

FIG. 5 is a left view thereof;

FIG. 6 is a front view of the sports bra with the straps of the sports bra uncrossed; and,

FIG. 7 is a rear view thereof.

The broken lines shown within the garment depict portions of the sports bra that form no part of the claimed design. The dot-dash lines in FIG. 1 depict environment that forms no part of the claimed design.
